[57] ABSTRACT

A subsurface drainage system consisting of a prefabricated lattice network of conduits mutually communicating with vertical inlets that extend upwardly through a pavement to allow entry of drainage fluid into the network. The vertical inlets are flared outwardly as they extend toward their intersection with the conduits for inhibiting clogging.

PAVEMENT DRAINAGE SYSTEM

The present invention relates to a prefabricated subsurface drainage system and more particularly to a drainage system for airport pavements.

The increasing demand for heavy duty airport pavements for safe all-weather operations is pointing up the need for the development of new design criteria for the pavement structure and the surface texture. One of the primary requisites for safe landing of high-speed aircraft in areas confronted with high rates of precipitation is an effective drainage system for the pavement surface. The present invention is directed to a prefabricated drainage system in rigid jointless airport pavements. This drainage system was designed for rapid removal of surface water from the pavement surface and a significant reduction in the volume of concrete required for a given pavement thickness.

The subsurface drainage system consists of a prefabricated network of lateral conduits with vertical inlets. The drainage system is to be prefabricated from an economical and easily formed material such as plastic. The rainfall intensity of the area in which the airport is to be located will dictate the size and spacing of the drainage inlets and laterals. The drainage system is to be located in the central portion of a concrete slab in view of the low level of flexural stress carried by this portion of the slab. In other words, a significant volume of concrete can be "formed out" (structural castellation) of the central portion of a beam without significantly reducing the structural performance. This unique drainage system was designed specifically for continuously reinforced concrete pavements, prestressed concrete pavements, and prestressed concrete panel components. The water collected by the drainage system is to be discharged into conventional storm drains outside of the pavement structure.

The prefabricated drainage system is to be incorporated in the pavement slab during construction or pouring. The two principal advantages associated with the prefabricated subsurface drainage system are safety and economy. The prompt removal of water from the pavement surface enhances the safety of landing operations by preventing hydroplaning of the aircraft. The removal of some percentage of the concrete from the central portion of the slab (forming concrete out) reduces the volume of concrete required for a given pavement thickness, thereby providing a more economical construction procedure.

These together with other objects and advantages which will become subsequently apparent reside in the details of construction and operation as more fully hereinafter described and claimed, specific reference being made to the accompanying drawings forming a part hereof, wherein like numerals refer to like parts throughout, and in which:

FIG. 1 is a perspective view of an airport pavement equipped with the present drainage system.

FIG. 2 is a top plan view of the airport pavement indicating the subsurface conduit members of the system.

FIG. 3 is a sectional view taken along a plane passing through section line 3-3 of FIG. 2.

FIG. 4 is a perspective view of a network section of the drainage system.

FIG. 5 is a sectional view taken along a plane passing through section line 5-5 of FIG. 4.

Referring to the figures, and more particularly FIG. 4, the drainage system network is generally indicated by reference numeral 10 and will be seen to include first lateral conduits 12 disposed in lattice relation to another set of lateral conduits 14. As more clearly shown in FIG. 2, conduits 22 are mutually parallel spaced as are the conduits 14. At each intersection between the lateral conduits 12 and 14 is vertical snorkel-

shaped inlet 16 that allows admission of surface pavement fluid into the drainage network.

As will be noted from FIG. 5, the cross section of each lateral conduit may fairly be characterized as teardrop shaped (20). The snorkel-shaped inlet 16 tapers inwardly as it extends upwardly along its intermediate length 22. An inlet port 24 is formed in each inlet and is adapted to be positioned in coplanar communication with an opening 25 in pavement surface 18.

- 10 The drainage network is recessed into the body of a pavement so that a first pavement deposit 28 underlies the network and forms vertical support therefor. A second pavement deposit 26 is disposed above the lateral conduits of the network and encircles the snorkel-shaped vertical inlets 16. It will of course be understood that the pavement deposits 26 and 28 merge in the void areas between lateral conduits thereby embedding these lateral conduits in place.

The present drainage network 10 may be incorporated in plant-produced structural components such as prestressed concrete pavement panels. Alternately, the drainage network may be placed in fresh concrete between two stages of pouring (multilift construction). Still further, the drainage network may be incorporated in continuously reinforced concrete pavements such as an integrated system for monolithic construction. The drainage network can be utilized as a support for the top layer of reinforcing steel. However, in a preferred embodiment, the network is embedded within prestressed or continuously reinforced concrete pavements having no joints.

The pavement 18 has the conventional cross or crown section characterized by a peak running along the centerline of the runway. The grade of slope of the runway causes water flow outwardly toward the runway sides during which time the water becomes drained by the subsurface drainage network of the present invention. As previously mentioned, the water collected by the network is fed to collector drains, such drains usually being positioned along both sides of the runway.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

- 45 1. Airport pavement construction comprising a concrete slab of substantially constant cross section throughout the extent thereof, said slab having upper and lower surfaces and a central area of minimum flexural stress therebetween, a prefabricated drainage system positioned as a unit within said central area and generally paralleling said upper surface through out the extent of the slab, said system including a network of spaced hollow elongated prefabricated conduits interconnected in a lattice pattern to define a plurality of spaced intersections, said slab extending monolithically over, under 50 and between said conduits to form a complete encasing thereof, fluid inlets associated with said conduit intersections, each inlet directly communicating with the intersecting conduits at the associated intersection and rising vertically therefrom through the overlying portion of the slab and terminated in an open upper end at the upper surface of the slab, the open upper ends of the inlets being orientated in spaced relation to each other with the upper surface of the slab being imperforate and continuous about the between said inlets and the open upper ends thereof.
- 55 2. The construction of claim 1 wherein the inlets comprise tubular members flared outwardly adjacent the intersections for inhibiting clogging thereof.
